JOHN B. FITZ-GIBBON, OF BRIDGEBURG, ONTARIO, CANADA, ASSIGNOR OF ONE-HALF
TO DREW M. THORPE, OF BUFFALO, NEW YORK

BASE FOR FURNACES, TANKS AND THE LIKE

Application filed December 22, 1927. Serial No. 241,934.

This invention relates to the construction of the bases or bottoms of furnaces or other structures adapted to contain molten metals, glass or other materials.

5 In the construction of the bottoms or base portions of metallurgical furnaces, of glass furnaces, or other containers for molten materials, blocks of refractory material are employed which are usually laid in courses 10 and which are intended to support the molten material. These blocks are subject to high temperatures which frequently cause cracking, burning or disintegration of the blocks, and it frequently happens that after a few 15 blocks have been worn away, additional bricks adjacent thereto or sometimes practically an entire course of blocks will float to the top surface of the molten material because of the greater specific gravity of the 20 molten material than that of the brick. In this way the bases or bottoms of containers for molten materials, as now constructed are soon destroyed, involving considerable expense to construct a new bottom or base, and 25 sometimes loss of material due to leakage created by the floating of blocks to the surface of the material.

The objects of this invention are to provide a bottom for a container of this kind 30 which is so constructed that the individual blocks used in the construction of the bottom of the container interlock with each other so that the destruction of one or more of the blocks does not enable other adjacent blocks 35 to float to the top of the molten material; also to produce a base or bottom for containers of this kind which is made up of interlocking units of comparatively simple form and which can easily be assembled or built 40 into a base or bottom; also to produce a base or bottom of this kind which is constructed to resist the discharge or leak of molten material through the same; also to improve the construction of the bottoms of 45 furnaces and other containers in other respects hereinafter specified.

In the accompanying drawings,

Fig. 1 is a central sectional elevation of the lower portion of a furnace provided with a bottom embodying this invention.

Fig. 2 is a fragmentary sectional elevation thereof, on an enlarged scale.

Fig. 3 is a fragmentary top plan view thereof.

Fig. 4 is a perspective view of one of the 55 blocks or units of the furnace or tank bottom, on an enlarged scale.

Fig. 5 is a perspective view of another block or unit.

Fig. 6 is a perspective view of a block of 60 modified construction.

Fig. 7 is a fragmentary, sectional elevation of a furnace or tank bottom constructed with blocks as shown in Fig. 6.

Fig. 8 is a fragmentary, top plan view of 65 the furnace or tank bottom shown in Fig. 7.

Fig. 1 illustrates my improved furnace bottom as applied to a blast furnace such as is commonly used in the smelting of iron, but it will be understood that the invention may 70 be applied to any other suitable type of container for molten material. The furnace shown includes an upright cylindrical wall A which rests upon a base B.

In constructing the base embodying my 75 invention I employ blocks, bricks, or units of any suitable or desired material which are so made that adjacent units interlock with each other in such a manner that destruction of a unit or of a portion of a unit will not cause 80 the dislodging of adjacent units and the floating of the same to the surface of the material in the container. In the particular construction shown in Figs. 1 to 5 inclusive, the 85 bricks or blocks are also so arranged that the blocks or blocks of two or more courses of horizontal tiers may interlock, so that none of the blocks of the upper course can become displaced or floated to the surface of the material while held by the blocks of a lower course. Such a structure may be produced by 90 means of blocks or bricks of any suitable or desired construction which have portions which interlock or interfit with corresponding portions of adjacent blocks. The blocks C and D shown in Figs. 1-5 show by way of example 95 one form or type of blocks which may be used for this purpose. The unit C illustrated in Fig. 4 includes top and bottom horizontal walls or surfaces 10 and 11 which are sub-

100

stantially flat and parallel to each other, front and rear walls 12 and 13 which are also preferably flat and extend vertically, connecting with the upper and lower surfaces 10 and 11, and opposite side walls 14 and 15 which converge from the opposite top and bottom walls 10 and 11 toward the middle portion of the block. Consequently the thickness or width of the block is greatest at the top and bottom faces 10 and 11 and least at the middle portion thereof.

The block or brick D shown in Fig. 5 is similar to one-half of the block C. This block has horizontal faces 20 and 21 of which the face 20 is substantially of the same area as the cross sectional area of the middle portion of the block C. The horizontal face 21 is substantially the same area as the faces 10 and 11 of the block C. The block also has opposite parallel vertical walls 22 and 23 corresponding to half of the horizontal walls 12 and 13 of the block C and the walls 24 and 25 of the block D converge from the horizontal walls 21 to the walls 20.

When a furnace or tank bottom is built with the use of blocks of this kind, the blocks C are so arranged that the horizontal walls 10 and 11 of one block will terminate at the middle portion of an adjacent block, as is clearly shown in Figs. 1 and 2. The base of the furnace or tank may be built up to any suitable or desired height, that shown in the accompanying drawings being built in two horizontal layers or sections, each of which is of a height equivalent to twice the height of the block C, thus forming an interruption of the mortar joints between the blocks of the two layers, but it will be obvious that the entire base may be built in a single layer of greater depth than those shown, to the height of three or more of the blocks C. It will be obvious that if the blocks C alone were used, the upper and lower surfaces thereof would not form a continuous surface, and consequently the half or filler blocks C are used at the upper and lower surfaces of the tier to fill the spaces between the blocks C.

By making the blocks C so that the ends thereof are larger than the intermediate portion, the various bricks or blocks of the bottom construction will be interlocked or dovetailed together. For example the blocks D used in the upper portion of the bottom as illustrated in Fig. 2 are held from floating upwardly because of the fact that the blocks C at opposite sides of each block D have their upper portions of greater size than their intermediate portions and consequently the blocks D are gripped or held by the blocks C and cannot rise to the surface of the material contained in the furnace or container. In a similar manner the blocks C which terminate on the upper surface of the bottom shown in Figs. 1 and 2 cannot rise to the surface for the reason that the lower portions thereof

are interlocked between the upper portions of the intermediate series of blocks C of the upper layer of blocks. If in time through corrosion or wear the upper surface of the bottom be worn down to a depth equivalent to the height of the blocks C, then the intermediate blocks C could not rise to the surface of the material in the furnace or container because of the fact that the lower portions thereof are held by the upper end portions of the lower blocks C of the layer, and also these intermediate blocks C would hold the remaining portions of the upper blocks D of the layer. Consequently it will be obvious that the bricks or blocks of the bottom construction cannot be floated to the top of the surface of the material contained in the tank or furnace. In other words, the blocks of one course are dovetailed into the adjacent horizontal course or courses and consequently are held in their correct positions without depending upon mortar or other bonding means to hold them in place. If the layer is to be made of greater depth than that shown, the lower blocks D shown in Fig. 2 can be replaced by the full sized blocks C and the construction can thus be continued throughout the full depth of the bottom, if desired. If this construction is employed all of the successive courses or tiers of bricks or blocks of the bottom will be interlocked one with another, while in the construction shown in Figs. 1 and 2 the bricks of one layer are not interlocked with those of another layer. In these constructions, however, the blocks of the two layers are staggered or arranged relatively to each other that the spaces between blocks of one layer are out of alignment with reference to the spaces between blocks of an adjacent layer.

In case it is desired to construct a furnace bottom in which each course or tier is so arranged with reference to other tiers that the joints between adjacent bricks are staggered in adjacent tiers, as may be desirable in some instances to prevent the escape of the molten material, the bricks or blocks C shown in Fig. 4 may be alternated with bricks or blocks E such as shown in Fig. 6 to produce the construction shown in Figs. 7 and 8. The block E is substantially similar to two blocks of the kind shown in Fig. 5 arranged end for end with their largest horizontal faces 21 adjoining. Consequently the block shown in Fig. 6 has upper and lower horizontal faces 30 and 31, side faces 32 and 33 which lie in upright planes and side faces 34 and 35 which incline or converge from the middle portions of the blocks toward the opposite ends thereof, or, in other words, toward the upper and lower faces 30 and 31 thereof. A block of this kind therefore is of greatest width at the intermediate portion thereof and when the blocks C are alternately arranged with the blocks E as is clearly shown in Fig. 7, a con-

struction is produced which results in an interlocking of the blocks of a course so that each block holds an adjacent block from rising and floating on the surface of the material contained in the furnace or tank. When blocks of this kind are used, the spaces between adjacent bricks or blocks may be staggered with reference to the spaces in adjacent tiers or courses, as clearly shown in Fig. 7.

The blocks described are of simple construction and can be inexpensively manufactured, but it will be understood that blocks of other construction, having one or more of their walls provided with parts adapted to interlock with adjacent blocks may be employed in place of those shown for the purpose of constructing bottoms for furnaces or containers embodying this invention.

I claim as my invention:—

1. A bottom for containers of molten materials, including blocks arranged in series of superposed horizontal courses and said blocks having their sides formed to cooperate with the sides of blocks of an adjacent course for interlocking the blocks of one course with those of another course.

2. A bottom for containers of molten materials, including a series of blocks having the upper portions of their sides formed to interlock with the lower portions of the sides of adjacent blocks, and having the lower portions of their sides formed to interlock with the upper portions of the sides of other blocks, whereby a horizontal course of blocks is interlocked with the course below.

3. A bottom for containers of molten materials, including a series of blocks having their top and bottom portions dovetailed, and arranged to have the blocks of one course fitting between blocks of an adjacent course, and blocks of single dovetail form fitting between upper and lower ends of the blocks of the structure to form flat top and bottom surfaces.

4. A furnace of the type adapted to contain molten materials, and having a bottom wall composed of abutting blocks laid side by side and in superposed courses, some of the blocks of one superposed course overrunning some of the blocks of the other course, the vertical faces of the abutting blocks being interlocked with one another in a manner to prevent individual vertical movement of any block, whereby individual blocks cannot be floated out of the wall, or the courses separated by the buoyancy of the molten material in contact therewith.

JOHN B. FITZ-GIBBON.
